CLAIM

The ornamental design for a container display rack, as shown and described.

DESCRIPTION

FIG. 1 is an isometric view of the container display rack showing the new design.

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front view thereof shown in an unassembled position; and,

FIG. 9 is an isometric view shown in an alternate position. The broken line showing is included for the purpose of illustrating environment and forms no part of the claimed design. The claimed container display rack, as shown in the drawings, includes a substrate with an opening with a first end and a second end. At the first end is a die-cut angle. At the second end is a die-cut post. The opening is used to receive a container with an angled top and a recessed bottom.
